[57] CLAIM

The ornamental design for a handset telephone with
articulated end, as shown and described.

DESCRIPTION

FIG. 1 is a front elevational view of a handset telephone
with articulated end showing our new design;

FIGS. 2 and 3 are respectively right and left side elevational
views thereof;

FIG. 4 is a rear elevational view thereof;

FIGS. 5 and 6 respectively top and bottom plan views
thereof;

FIG. 7 is a left side elevational view thereof, with three
articulated sections in an articulated position; and,

FIG. 8 is a front elevational view thereof, with the three
articulated sections in the position shown in FIG. 7.

FIG. 1

FIG. 2
